UNITED STATES PATENT OFFICE.

RICHARD P. SCHENK, OF EAST ORANGE, NEW JERSEY.

ALBUM FRAME.

Application filed June 24, 1925. Serial No. 39,185.

This invention relates to devices for exhibiting pictures and like flat thin objects whereby they are held in a manner conducive to observation but protected from 5 injury.

One of the objects of the invention is to provide a rigid rectangular frame, of any desired size and proportions, having a transparent front panel and an opaque back 10 hingedly engaged at one of its edges.

A further feature is in the provision of an effective closure spring exerting pressure upon the back to maintain the exhibited object smoothly and firmly against the panel 15 so that the object is displayed in the best possible manner.

Another aim is to produce a simple and inexpensive album frame in which exhibited objects may be quickly and conveniently 20 changed, substitution being effected entirely by hand without the use of tools or extraneous appliances.

These objects are attained by the novel construction and arrangement of parts 25 hereinafter described and shown in the associated drawings, constituting a material part of this disclosure, and in which:—

Figure 1 is a rear side elevational view 30 of an album frame made in accordance with the invention.

Figure 2 is an edge view of the same.

Figure 3 is a fragmentary cross sectional view taken on line 3—3 of Figure 1, and drawn to an enlarged scale.

The embodiment of the invention illustrated is composed of a rigid rectangular frame having side members 5 and 6, respectively at the front and rear edges, their 35 ends being mitered as at 7 and connected by members 8, all of these members having inwardly extending flanges, as at 9, arranged in the manner of an ordinary picture frame.

Seated on the flanges 9 is a flat level trans- 40 parent panel 10 and disposed against the panel is a mat 11, cut out in the usual manner to expose the face of a picture 12 or similar object, these several elements being of the usual type of construction.

In common frames a plate, generally 45 termed a backing board, is secured by brads or like fastening means, but in the present invention a rigid plate 14 is fitted to enter the opening at the back of the frame and 50 engaged by hinges 15, one of their leaves being fixed on the rear surfaces of the frame

element 6 and their other leaves being similarly secured to the outer surface of the plate 14.

These hinges have, as a pintle, a unitary 60 rod 16 extending straight through the looped elements of both the hinges, from one to the other and is disposed substantially in the plane of the inner edge of the frame side 6.

A spring wire is bent at its center to produce an eye 17 extending over the surface of the plate 14, to which it is secured by a screw 18.

Reaching from the eye 17 are angularly 70 disposed arms 19 formed into right and left hand coils 20 encircling the rod 16, these coils having oppositely extending end members 21 disposed parallel to the rod, adjacent the hinges and terminate in out- 75 turned projections 22 disposed on the hinge leaves secured on the frame side 6, this arrangement being clearly shown in Figure 1.

Thus it will be seen that a torsional 80 effect is produced by the spring device to press against the plate 14 to normally retain it in a closed position.

Near the front edge of the plate 14 is a 85 ring 23 held by a hasp 24 set in the plate, providing means for turning the plate upon its hinges to an open position when desired, as in changing the object 12.

Buttons 25 adapted to overlie the front 90 edge of the plate 14, are pivoted on screws 26 set in the rear surface of the frame element 5, these buttons obviously acting as clamps to retain the plate 14 in firm engagement with the back of the object 12.

While a certain preferred embodiment of 95 this device has been shown and described, it will be understood that changes in the form, arrangement, proportion, size and details thereof may be made without departing 100 from the scope of the invention as defined in the appended claims.

Having thus described my invention, what I claim as new and desire to secure by Letters Patent, is:—

1. An album frame comprising in combination with an open oblong rectangular frame structure adapted to receive a flat display object, of a plate hingedly engaged to one of the longer sides of said frame to rest upon the object, a single torsional 110 spring combined with the plate hinges to press the frame carried leaves, half of said

- spring being coiled right handed and half left handed, and a bight formed at the center of said spring to impinge upon said plate.
- 5 2. An album frame comprising in combination with an open oblong rectangular frame and a plate fitting the opening in the frame, of a pair of spaced hinges, each having one leaf fixed on one of the longer 10 frame elements, the other leaves of said hinges being fixed on said plate, a single straight pintle rod for both hinges, a unitary spring encircling said rod having out-turned ends resting on the frame fixed leaves 15 of the hinges, an oppositely directed element midway in the length of the spring extending over said plate, an eye formed in said element, and a screw passing through said eye into said plate.
3. An album frame comprising in combination with an open oblong rectangular frame, of a plate fitting the frame, a pair of spaced hinges connecting the plate to one of the longer frame members, said hinges having a pintle rod common to both and extending therebetween, a spring wire having an eye fixed on said plate and oppositely coiled ends encircling said rod in opposite relation, the ends of the encircling coils being outturned to rest upon the fixed leaves 20 of said hinges, a ring carried by said plate to facilitate openings, and buttons pivoted on the opposite member of said frame to hold the plate in closed position.
- 25 In testimony whereof I have signed my name to this application.

RICHARD P. SCHENK.
